UNITED STATES PATENT OFFICE.

ROY FRANCIS ENSIGN, OF PASADENA, CALIFORNIA.

MEANS FOR AND METHOD OF IGNITING FUEL.

1,376,194.

Specification of Letters Patent. Patented Apr. 26, 1921.

Application filed January 21, 1918. Serial No. 213,060.

To all whom it may concern:

Be it known that I, ROY FRANCIS ENSIGN, a citizen of the United States, residing at 903 Oakland avenue, in the city of Pasadena, county of Los Angeles, and State of California, have invented and discovered a new and useful Means for and Method of Igniting Fuels, of which the following is a specification.

10 This invention relates to a spark plug which is adapted for lighting mixtures of liquid fuel and air in combustion chambers or in the open air and I have discovered that by holding liquid hydrocarbon or 15 the like fuel in the form of a disk by capillary attraction in the center of a gap between two surfaces and causing an electric arc between two points in close proximity to an edge of the liquid disk thus held, a 20 sheet of flame will be produced practically in parallelism with the gap.

An object of the invention is to insure a clear and free passage for the electric spark irrespective of the presence of a quantity of 25 liquid fuel between the electrodes. A principle of the invention and discovery is the employment of capillary attraction to insure such clearance of electrode surfaces to allow the electric current to form an arc, 30 despite flooding the electrodes with liquid fuel, and to effectively deliver fuel to such arc to form a flame.

Further objects are simplicity, ease of construction and certainty of action.

35 The discovery and invention is applicable in various forms and for various purposes, the essential feature being the juxtaposition of two electrode faces unobstructed throughout and of sufficient area to cause 40 a capillary attraction sufficient to draw from the electrode margins to and toward the electrode axis any fuel contacting with the electrode faces, so as to clear the passage for an electric spark between part or all of 45 the rims or edges of the electrodes.

Other objects, advantages and features of invention may appear from the accompanying drawing, the subjoined detail description and the appended claims.

50 The accompanying drawing illustrates

the invention in a form deemed most advisable.

Figure 1 is an axial section of a spark plug constructed in accordance with this invention and ready for insertion into and 55 connection with a combustion chamber, not shown.

Fig. 2 is a plan of the under side of the spark plug shown in Fig. 1.

Fig. 3 is a face view of the two electrodes 60 detached.

Fig. 4 is an enlarged side elevation of the two electrodes with a body of liquid hydrocarbon held by capillary attraction between the juxtaposed faces in the presence 65 of air and ignited by an electric arc at one edge, thus producing a sheet of flame.

The disconnected and entirely separate electrodes 1, 2, are of the same peripheral form and dimensions preferably circular as 70 shown, and their juxtaposed faces are plain and flat and continuous and unobstructed throughout and are arranged in parallelism to each other and are spaced apart a short distance relatively small compared to 75 the diameter of the electrode faces *a, b*.

In practice I have used circular electrodes $\frac{3}{8}$ ths of an inch diameter spaced $\frac{1}{2}$ nd of an inch apart and arranged co-axially.

In the drawing the electrode 2 is supported from a tubular shell 3 by means of angular or bent wire brackets 4, the radial arms 5 of which are inserted in sockets 6 bored into the edge of the electrode 2. The parallel limbs 7 are inserted into holes 8 in 85 the inner end of the shell 3 which is threaded at 9 for insertion into a suitable support. The shell is provided at its upper end with a seat 10 to receive the collar 11 of the porcelain insulator 12 and the upper end of the shell 3 is threaded at 13 to receive the gland nut 14 which screws down upon the collar 11 to hold the insulator 12 in place. The electrode 1 is provided with a central socket 15 in which is 90 fixed the conductor 16 which may be a rod or wire of the usual noncorrosive conducting material such as nickel alloys. The electrodes and brackets are also preferably 95 made of the said material. The outer end 100

of the conductor 16 is threaded at 17 to receive the binding nut 18 which is of the usual construction and contacts with the lead 19 to conduct the current to the electrode 1. The shell 3 is screwed into the conducting material, not shown, which forms the ground for the circuit.

In practical use the electrodes are not intended to be submerged in the fuel and 10 if any limited quantity of the fuel such as liquid hydrocarbon comes into contact with the adjacent faces of the electrodes it will not obstruct the circuit, but will be sufficiently drawn by capillary attraction from the peripheries of the electrodes to allow the electric spark to jump across the gap between the electrodes. The effect is to 15 gasify and ignite the edges of a sheet of liquid fuel thus held centrally between the electrodes; and thereupon a long stream of 20 ignited gas will be shot radially from the spark gap, thus producing a very sudden and violent ignition of the fuel vapors surrounding the electrodes.

With the construction set forth, under 25 operation in the open air, an arc will be formed by the circuit across the gap between the electrode surfaces *a*, *b*: but if the electrodes are submerged in liquid hydrocarbon, the circuit is thereby kept open and 30 the electrodes are insulated from each other. It is therefore understood that the spark plug is not adapted for ignition when the electrodes are so submerged, but is only expected to be effective under ordinary circumstances when the edges or some portion 35 thereof may be kept free, so that the spark may jump from one to the other of such free portion.

40 By reference to Fig. 4 it will be understood that the edges *c* of the liquid hydrocarbon fuel sheet *d* are attenuated and the peripheral surface of such sheet is extended by the grooved character thereof to large 45 contact with the surrounding air so that upon the passage of the spark or arc *e*, ignition is effected and the production of a large volume of hydrocarbon vapor or gas is produced which burns as a lateral flame *f*.

50 The attenuated upper and lower edges of the liquid fuel sheet ignite with great facility and it is understood that the attenuation and the ignition may be effected by any means suitable to those purposes respectively 55 and that the supply of fuel to such edges may result from the condensation from a mixture of air and fuel circulating in the vicinity of the electrodes.

The ignition particularly desired in this 60 connection is the first ignition in starting combustion in a chamber or in the open air, and it is observed that when the electrodes are within a heated chamber the oil is dissipated by the heat and the necessity of igni-

tion by the method and means is suspended 65 until the electrodes and the surroundings become cool enough to allow an accumulation of the liquid fuel to again occur between the electrodes.

By this invention and discovery drowning out of the ignition is easily avoided in all ordinary oil burning practice.

It is understood that at the outset the arc will jump as indicated at *e* but that immediately after the flame *f* is produced the 75 current flows through the volatilized carbon, the combustion of which supports the flame. Consequently the electric current and the vapors unite in their action to produce a large body of flame surface to ignite 80 the flowing air and fuel mixture that is to be combusted.

I claim:—

1. A spark plug provided with electrodes having juxtaposed surfaces and being 85 spaced apart to form a gap that is unobstructed throughout the space within the perimeters of said surfaces and being of diameters sufficiently exceeding the width of the gap between said surfaces to allow capillary 90 attraction acting upon liquid fuel between the electrodes to withdraw from the electrode edges a sufficient portion of such fuel to expose the edges of the electrode to allow the passage of the spark between 95 the electrodes though they are drenched with such fuel.

2. A spark plug comprising two electrodes having flat juxtaposed surfaces spaced apart to form a gap diametrically coextensive with the electrodes and unobstructed from either of them and of considerably less width than the diameter of the electrode faces so that capillary attraction may act to 100 free the edges from the presence of liquid 105 hydrocarbon fuel in case the same comes in contact with such faces.

3. A spark plug comprising electrodes having disk-like flat opposed faces spaced apart a distance sufficiently less than the 110 diameter of said disk-like faces to allow capillary attraction to hold liquid fuel at the centers of the gap and to sufficiently free the edges of the electrodes to allow an electric spark to jump across the gap irrespective of the presence of liquid hydrocarbon 115 on such electrodes insufficient in quantity to submerge the faces of the electrodes.

4. The method of igniting mixtures of 120 liquid fuel and air which consists in holding an air surrounded sheet of such fuel by capillary attraction and producing an electric arc at an edge of such sheet.

5. The method set forth of igniting mixtures of liquid fuel and air which consists in attenuating air surrounded edges of a sheet of such liquid fuel by means of

capillary attraction between flat unobstructed faces of two terminals and igniting the attenuated edges.

6. The method set forth of igniting mix-
5 tures of liquid fuel and air which consists
in attenuating an edge of a sheet of such
liquid in air and igniting the attenuated
edge.

7. The method set forth of igniting mix-
10 tures of liquid fuel and air which consists in

attenuating an edge of a sheet of such liquid in air and producing an electric arc at such edge, thereby igniting the attenuated edge.

In testimony whereof, I have hereunto set 15
my hand at Los Angeles, California, this
11th day of January, 1918.

ROY FRANCIS ENSIGN.
